SWIVEL MIRROR

Orloff W. Holden, Chicago, Ill.

Application January 30, 1957, Serial No. 44,659

Term of patent 14 years

(Cl. D33—9)

Figure 1 is a perspective view of a swivel mirror showing my new design;

Figure 2 is a side elevational view with the mirror in a slightly different position; and

Figure 3 is a front elevational view.

I claim:

The ornamental design for a swivel mirror, as shown.
